UNITED STATES PATENT OFFICE.

FREDRIC BILLINGS, OF MARINETTE, WISCONSIN, ASSIGNOR OF ONE-HALF
TO H. C. HIGGINS, OF SAME PLACE.

THREE-WAY VALVE.

SPECIFICATION forming part of Letters Patent No. 579,465, dated March 23, 1897.

Application filed December 19, 1896. Serial No. 616,356. (No model.)

To all whom it may concern:

Be it known that I, FREDRIC BILLINGS, a citizen of the United States, residing at Marinette, in the county of Marinette and State of Wisconsin, have invented certain new and useful Improvements in Three-Way Valves; and I do hereby declare the following to be a full, clear, and exact description of the invention, such as will enable others skilled in the art to which it appertains to make and use the same.

My invention relates to improvements in three-way valves for admitting exhaust-steam to condensers or for any other similar purpose, the object being to produce a valve which will automatically admit the steam to or shut off the steam from the condenser at the proper intervals.

Reference is had to the accompanying drawings, wherein the same parts are designated by the same letters of reference throughout the several views.

Figure 1 is a central sectional view of a valve constructed in accordance with my invention, the section being taken on the line 1 2 of Fig. 3, showing the valve in its normal position. Fig. 2 is a similar view showing the valve in the position to admit steam to the condenser. Fig. 3 is a sectional view of the device, taken on the line 3 3 of Fig. 2, looking in the direction of the arrows; and Fig. 4 is also a sectional view taken at right angles to Figs. 1 and 2 on the line 4 4 of Fig. 1, looking in the direction of the arrows.

35 A designates the valve-casing, which is bored through centrally, as at A', and provided with a flange a', by which it is connected with the pipe leading to the condenser, the pipe and condenser being omitted from the drawings, as they form no part of the present invention. The central opening of the casing is enlarged at the opposite end to its junction with the condenser-pipe to form a valve-chamber A², in which chamber a valve B of the plunger type is arranged to slide. An annular chamber C is formed around the central opening and separated therefrom by the partition-wall a, which has an annular vent a² opening into the valve-chamber A². The chamber C is connected with the pipe leading from the exhaust of the engine.

through the opening C', which is flanged, as at c', to make the proper connection.

At the opposite side of the valve from the opening C' (or at any other suitable point) is formed an opening D, which is open to the atmospheric air at all times, and a vent A³, formed in the partition-wall a³ of the valve-casing, opens communication from the chamber C to the opening D and thence to the atmospheric air. A rod E, having thereon a squared portion, as shown at e, is journaled at one end in one side of the opening D, just above the vent A³, and at the other end it passes through the other side of the opening D and through the stuffing-box E, and at this latter end has a lever or handle E mounted thereon, as seen in Figs. 3 and 4. A flap-valve H is hung upon the central squared portion e of the rod E and normally rests over the mouth of the vent A³, forming a check-valve to prevent the atmospheric air from entering the said vent, but to allow the steam in the chamber C to escape when the steam-pressure therein exceeds the pressure of the atmospheric air without.

The valve B is of a cylindrical form, closed at its upper end and open at its lower end, and is arranged to slide closely in the valve-chamber A². The said valve B is provided with ports b, which open through its side at the proper points to register with the vent a² when the valve is in its lower position.

The upper end of the valve-chamber A² is closed by a perforated cap-piece I, through the perforations i of which the atmospheric air may exert its pressure upon the top of the valve B. Through the central perforation i' of the cap-piece I the valve-rod B' passes and is secured to or formed integral with the closed head of the valve B. The upper end of the valve-rod B' is screw-threaded to receive the nuts b', and a spiral spring b² surrounds the said valve-rod and bears at one end against the nuts b'. The tendency of this spring b² is to keep the valve B normally raised to the position shown in Fig. 1—i. e., with the annular rib b³ on the head of the valve resting against the under side of the cap I and the lower cylindrical part closing the vent a², thus preventing the steam, should it enter the chamber C, from entering the condenser.

An opening K is formed in the casing A over the check-valve H, through which the said check-valve may be removed when necessary, and the said opening is normally covered by a cap-piece k, held in place by bolts k', as shown in Figs. 1, 2, and 4.

- The operation of the device is as follows: When the condenser is in operation and full of steam, the valve B will remain in its raised position, thus cutting off the flow of steam from the condenser. As the steam is condensed a partial vacuum will be formed in the condenser, which will relieve the pressure below the valve B and allow the atmospheric pressure on top of the valve to overcome the tension of the spring b² and press the valve downwardly to the position shown in Fig. 2, thus opening the vent a² and allowing the exhaust-steam to pass into the condenser. As soon as the condenser is filled with steam the partial vacuum is destroyed, and the valve B will return to its raised position and shut off the steam from the condenser. This operation is repeated each time the partial vacuum in the condenser becomes sufficient to allow the outer atmospheric pressure to open the valve B. As soon as the vent a² opens the rushing of the steam into the condenser will create a partial vacuum in the chamber A³ on the inner side of the valve H, and the said valve will be forced firmly upon its seat by the outer atmospheric pressure, thus shutting off the atmospheric air from the engine. An elastic gasket h is provided upon the valve H to bear upon the valve-seat and form a close connection. When the condenser is not in operation, whether by reason of the fact that it has been purposely shut down or has suffered an accident, or for any reason whatever has become inefficient, the valve B will retain its position at the extremity of its upward stroke, thus effectually closing the channel between the engine and the condenser and forcing the exhaust-steam to travel around through the chamber C and exert its power or pressure against the check-valve H and by so doing cause the said check-valve to swing outward upon its stem or fulcrum-rod E and in so doing open a passage between the chamber C and the opening D, thus allowing the exhaust-steam a free passage from the engine through the opening C' into chamber C and thence through the opening D to the outer air. If at any time during the operation of the condenser from any cause whatever the partial vacuum created in the condenser is not sufficient to cause the valve B to open the vent a², then the exhaust-steam will be diverted from the condenser and will pass around in the chamber C and out through the opening A³, raising the check-valve H. When the condenser has begun to properly operate and a sufficient partial vacuum is once more created beneath the valve B to allow the atmospheric pressure to overcome the tension of the spring b² and force the valve B downwardly, the vent a² will be opened and the steam again

turned into the condenser. Thus the operation of turning the exhaust-steam into or away from the condenser is performed automatically, the condenser being supplied with steam as long as it is operating properly, but the steam being cut off when the condensation ceases or is imperfectly performed.

While this invention is described as a safety device for steam-condensers, it will be understood that it may be used for other purposes, and I therefore do not desire to limit myself to this specific use or to the precise details of construction herein described, as many modifications might be made therein without departing from the spirit of the invention.

The advantages of this invention will be clearly apparent to those skilled in the art to which it appertains.

Having thus described my invention, what I claim, and desire to secure by Letters Patent of the United States, is—

1. In a three-way valve, the combination with a casing having a central passage, a valve-chamber opening into the said central passage, a steam-chamber surrounding the said valve-chamber, a vent opening from the surrounding chamber into the said valve-chamber, an opening to admit steam to the said steam-chamber, an opening from the steam-chamber to the outer or atmospheric air, and a check-valve controlling the said opening, of a valve arranged to slide in the said chamber, and open or close the said vent, substantially as described.

2. In a three-way valve, the combination with a casing having a central passage, a valve-chamber opening into the said central passage, a steam-chamber surrounding the said valve-chamber, a vent opening from the surrounding chamber into the said valve-chamber, an opening to admit steam to the said steam-chamber, an opening from the steam-chamber to the outer or atmospheric air, and a check-valve controlling the said opening, of a valve arranged to slide in the said valve-chamber and having ports adapted to register with the said vent and open or close the same, substantially as described.

3. In a three-way valve, the combination with a casing having a central passage, a valve-chamber opening into the said central passage, a steam-chamber surrounding the said valve-chamber, a vent opening from the surrounding chamber into the said valve-chamber, an opening to admit steam to the said steam-chamber, an opening from the steam-chamber to the outer or atmospheric air, and a check-valve controlling the said opening, of a valve arranged to slide in the said valve-chamber and having ports adapted to register with the said vent, a valve-rod on the said valve and a spring on the said valve-rod adapted to normally hold the valve in the closed position, substantially as described.

4. In a three-way valve, the combination with a casing having a central passage, a valve-chamber opening into the said central

passage, a steam-chamber surrounding the said valve-chamber, a vent opening from the surrounding chamber into the said valve-chamber, an opening to admit steam to the 5 said steam-chamber, an opening from the steam-chamber to the outer or atmospheric air, a rod journaled in the casing, a check-valve hung upon the said rod and adapted to cover the opening to the atmospheric air, and 10 a handle on the end of the rod; of a valve arranged to slide in the said valve-chamber and

having ports adapted to register with the said vent; a valve-rod on the said valve, and a spring on the said valve-rod adapted to hold the valve in its closed position, substantially 15 as described.

In testimony whereof I affix my signature in presence of two witnesses.

FREDRIC BILLINGS.
